AUTOMATIC STOP GAUGE FOR WINDING MACHINES

Charles W. Guion, Arlington, Va.

Application February 2, 1949, Serial No. 74,167

10 Claims. (Cl. 242—39)

(Granted under the act of March 3, 1883, as amended April 30, 1928; 370 O. G. 757)

1

The invention described herein, if patented, may be manufactured and used by or for the Government for governmental purposes, without the payment to me of any royalty thereon.

This invention relates to automatic stop motions for winding machines and has for its primary object to generally improve devices of this type.

More specifically, it is an object of the present invention to provide an electrically-operated stop gauge mechanism which will serve to stop the winding of a spool or cop when the desired amount of thread has been wound thereon.

A further object of the invention resides in the provision of such a stop mechanism which may be readily adjusted to vary the stopping of the spool or cop in accordance with a predetermined amount of thread that it is desired to wind.

It is a still further object of the invention to provide a series or gang of stop mechanisms all of which may be simultaneously adjusted at a single operation.

Another object of the invention resides in the provision of an electrically-operated stop mechanism which may be readily installed on winding machines of the type shown in J. O. McKean Patent No. 1,958,060, in which the spools are automatically stopped if the thread breaks or becomes exhausted.

Another object of the invention consists in providing an electrically-operated stop mechanism in which the electric circuit is automatically opened immediately after the stop mechanism has been activated.

Other objects and advantages of the invention will be apparent from the following description when taken in connection with the accompanying drawings, in which

Figure 1 is a vertical transverse sectional view of the winding machine of Patent No. 1,958,060, showing the improved stop mechanism installed thereon.

Figure 2 is an enlarged front elevational view, partly broken away, of a battery or gang of micro-switches and showing the structure by which they may be simultaneously adjusted to determine the size of the packages to be wound, and

Figure 3 is a fragmentary front elevational view of the machine with parts omitted for the sake of clearness.

The automatic electric stop gauge forming the subject matter of the present invention is primarily intended for installation on winding

2

machines of the type shown in the McKean patent referred to above, and inasmuch as this mechanism is clearly shown in that patent and is a well-known commercial item, it is deemed necessary to show in the present illustration only such features of the winding machine as cooperate directly with the attachment. This stop mechanism for gauging the size of the wound cones may with slight modifications in structural details be employed on other types of winding mechanisms.

The numeral 1 indicates the upper portion of the frame of the mechanism, while the numeral 2 represents a series of cones to be simultaneously wound, and the numeral 3 indicates winding rolls operated by motive power from any suitable source and adapted to engage and rotate the cones 2. In the winding machine of the present illustration, the cones or spools are mounted on spool holders which are carried by pivoted arms 4, and which arms are controlled by the mechanism indicated generally by the numeral 5 to raise the spools or cones 2 from the winding rolls 3, when the thread breaks or is exhausted.

The particular mechanism for causing a discontinuance of the winding operation when the thread breaks or is exhausted comprises a detector wire 6, which is pivoted to the frame 1, and is normally held in the position shown in Figure 1 by the thread 8, which is being wound from the bobbin 9, onto the spool or cone 2. Associated with the pivot 7 is a tripping roller 10, adapted to cooperate with a kicker cam 11, when the detector wire 6 is allowed to move upwardly about its pivot 7, by reason of the breaking or exhausting of the thread 8. This movement of the kicker cam will throw the roller 10 out of the path of the cam, and thereby operate the mechanism indicated generally by the numeral 5, to permit a spring 12 to raise the spool 2 out of contact with the winding roll 3, thereby discontinuing the winding operation. This mechanism is all shown and described in the McKean patent, as previously referred to.

The attachment of the present invention comprises a series of electrical switches 20, which are mounted on arms 21, which are in turn fixed to an oscillatable shaft 22, supported in hangers 23, secured to the under surface of the frame 1. This shaft 22 is preferably provided with screw threads at each end for co-operation with wing nuts 24, by means of which

the shaft may be firmly secured in any position to which it may be set. By thus adjusting the arms 21 toward or from the spools 2, the size of the completed spools may be varied since, as will appear hereinafter, the mechanism for disassociating the spools from the winding rolls 3 is set in operation when the switches 20 are closed by contact with the completed spools or packages.

As hereinbefore stated, the stop mechanism of the McKean patent is operated when the detector wire is allowed to rise by reason of the breaking or exhaustion of the thread 8, and the present improvement resides in providing additional means for raising the detector wire 6, when the spools are filled regardless of whether the thread 8 is broken or exhausted. This mechanism comprises a solenoid 25 so positioned that its plunger 26, when retracted will be in engagement with the underside of the detector wire 6, when the latter is held in its lowered position by the thread 8 being wound upon the spools. When one of the circuits in which the respective solenoids 25 and switches 20 are mounted is closed, the plunger 26 will raise the particular detector wire 6, thereby setting in operation the mechanism heretofore described by means of which the lever 4 is caused to rise so as to disengage the particular spool 2 from its roller 3, thereby discontinuing the rotation of the particular spool.

The switches 20 are so disposed with relation to the oscillatable shaft 22 as to form an angle of about 28° with the vertical in the present illustration, and this angle will be increased as the arms 21 and the switches 20 are adjusted so as to stop the mechanism in the formation of larger packages. A particular advantage of this construction is that the switches 20 are allowed to open just as soon as the mechanism 5 has been set in operation to lift the spools 2, thereby preventing heating of the coils.

By means of the construction described herein, it will be apparent to those skilled in the art that the stop mechanism may be readily adjusted to vary the size of a spool being wound, that the stop mechanism may be simultaneously adjusted for all of the spools by a suitable adjustment of the shaft 22, and that the switches are mounted so as to be automatically opened when the winding operation is discontinued and thereby prevent heating of the solenoid coils.

In accordance with the patent statutes, I have described herein what I now consider to be the preferred form of the invention suitable for installation upon the McKean winding machine; but it is to be understood that the mechanism may be modified as to various details for installation on other types of winding machines without in any way departing from the spirit of the invention, and it is intended that all such variations be included within the scope of the appended claims.

I claim:

1. In a winding machine including a plurality of spool holders and means for rotating a spool mounted thereon, electric circuits including electrically-operated means for causing the discontinuance of the winding operations, a shaft mounted for adjustment about its axis, electric switches in said circuits, said switches being fixed to the shaft and disposed adjacent the spool holders.

2. In a winding machine including a winding roll, a spool holder for cooperation therewith, and means for moving one of said elements bodily

5 with respect to the other, a detector wire for controlling said movement, electrically-operated means for moving the detector wire, said last-named means including an electric switch disposed adjacent the movable element.

3. In a winding machine including a winding roll, a spool holder, and means for moving the spool holder toward and from the winding roll, a detector wire for controlling the movements of the spool holder, a solenoid for operating the detector wire, an electric circuit for the solenoid, and an electric switch in said circuit mounted adjacent the spool holder.

4. In a winding machine including a winding roll, a spool holder for cooperation therewith, and means for moving one of said elements bodily with respect to the other, a detector wire for controlling said movement, electrically-operated means for moving the detector wire, said last-named means including an electric switch disposed adjacent the spool holder, and means for adjusting the switch toward and from the spool holder.

5. In a winding machine including a series of 15 winding rolls, a series of spool holders for cooperation therewith, and means for moving the spool holders toward and from the winding rolls, detector wires for controlling the movement of the spool holders, electrically-operated means for moving the detector wires, said last-named means including electric switches disposed adjacent the spool holders, and means for simultaneously adjusting all of said switches toward and from said spool holders.

30 6. In a winding machine including a series of winding rolls, a series of spool holders for cooperation therewith, and means for moving the spool holders toward and from the winding rolls, detector wires for controlling the movement of the spool holders, electrically-operated means for moving the detector wires, said last-named means including a rotatable shaft, a plurality of electric switches fixed to said shaft and disposed adjacent the respective spool holders, and means for securing said shaft in various adjusted positions.

35 7. In a winding machine including a winding roll, a spool holder for cooperation therewith, means for moving one of said elements bodily with respect to the other, and a detector wire for controlling the movements of the spool holder in accordance with the tension on a thread passing thereover, a solenoid for moving said wire, an electric circuit for the solenoid, an oscillatable arm mounted adjacent the spool holder, an electric switch in said circuit and mounted on said arm, and means for securing the arm in various adjusted positions.

40 8. In a winding machine including a spool holder, a winding roll for cooperation therewith, means for lifting the spool holder, and a detector wire for controlling the lifting of the spool holder, electrically-operated means for moving the detector wire, said last-named means including an electric spring switch disposed adjacent the spool holder and arranged at an angle to the vertical, whereby the circuit is closed when the spool is wound to a predetermined size and is automatically opened when the spool is lifted.

45 9. In a winding machine including a winding roll, a spool holder for cooperation therewith, means for lifting the spool holder bodily with respect to the winding roll, and a detector wire for controlling the movement of the spool holder in accordance with the tension on a thread passing

over the detector wire, separate means for operating the detector wire, said last-named means including control means disposed adjacent the spool holder for activating the separate means when the wound thread reaches a predetermined diameter.

10. In a winding machine including a winding roll, a spool holder for cooperation therewith, means for lifting the spool holder bodily with respect to the winding roll, and a detector wire for controlling the movement of the spool holder in accordance with the tension on a thread passing over the detector wire, separate means for operating the detector wire, said last-named means including control means disposed adjacent the spool holder for activating the separate means when the wound thread reaches a predetermined diameter, said control means being inclined downwardly toward the spool holder, whereby when

the spool holder is lifted the control means is rendered inoperative.

CHARLES W. GUION.
